UNITED STATES PATENT OFFICE

93,032

DESIGN FOR RUBBERETTE MATERIAL

Harry Sigmund Mayer, South Norwalk, Conn.

Application May 23, 1934, Serial No. 51,891

Term of patent 14 years

To all whom it may concern:

Be it known that I, HARRY SIGMUND MAYER, a citizen of the United States of America, and resident of the city of South Norwalk, county of Fairfield, and State of Connecticut, have invented a new, original, and ornamental embossed Design for Rubberette Material, of which the following is a specification, reference being had to the accompanying drawing, forming a part thereof.

The figure is a plan view of a portion of the

rubberette material, showing my new embossed design.

The portion of the design shown within the dot and dash lines constitutes a unit of the design so that if the left side were placed alongside the right, there will exist a continuation of the design.

I claim:

The ornamental embossed design for rubberette material, as shown and described.

HARRY SIGMUND MAYER.
